HYDRAULICALLY DRIVEN TOOL FOR COMPRESSING HELICAL SPRINGS

Kaare Heen, 7 Knausveien, 3100 Tonsberg, Norway
Filed Dec. 6, 1974, Ser. No. 530,474

Claims priority, application Norway June 10, 1974

Term of patent 14 years

Int. Cl. D15—99

U.S. Cl. D54—13 R

Fig. 1.

Fig. 2.

Fig. 3.

FIG. 1 is a perspective view from one side of a hydraulically driven tool for compressing helical springs showing my new design;

FIG. 2 is a plan view of said hydraulically driven tool for compressing helical springs;

FIG. 3 is an underplan view of said hydraulically driven tool for compressing helical springs;

FIG. 4 is an elevation of other side of said hydraulically driven tool for compressing helical springs;

FIG. 5 is a front view of said hydraulically driven tool for compressing helical springs.

I claim:

The ornamental design for a hydraulically driven tool for compressing helical springs, as shown.
